[57] CLAIM

The ornamental design for a marking caliper, as shown and described.

DESCRIPTION

FIG. 1 is a front elevational view of a marking caliper showing my new design;

FIG. 2 is a rear elevational view;

FIG. 3 is a right side elevational view;

FIG. 4 is a left side elevational view;

FIG. 5 is a top plan view;

FIG. 6 is a bottom plan view;

FIG. 7 is a cross-sectional view as taken along line 7—7 of FIG. 1; and

FIG. 8 is a cross-sectional view as taken along line 8—8 of FIG. 1 thereof.

FIG. 1
